UNITED STATES PATENT OFFICE.

HENRY B. DIERDORFF, OF COLUMBUS, OHIO, ASSIGNOR TO THE JEFFREY MANUFACTURING COMPANY, A CORPORATION OF OHIO.

MINING-MACHINE.

1,081,818.

Specification of Letters Patent. Patented Dec. 16, 1913.

Application filed October 25, 1909. Serial No. 524,416.

To all whom it may concern:

Be it known that I, HENRY B. DIERDORFF, citizen of the United States, residing at Columbus, in the county of Franklin and State of Ohio, have invented certain new and useful Improvements in Mining-Machines, of which the following is a specification, reference being had therein to the accompanying drawing.

10 This invention relates to improvements in mining machines and more especially those of the breast or front thrust type.

The objects of the invention are to provide an improved frame for mining machines of this type, and also to provide certain other improved structural features which will be described in the following specification.

Of the drawings Figure 1 is a plan view 20 of a mining machine embodying my invention, the driving motor being removed for the purpose of more clearly showing the gearing. Fig. 2 is a side elevation. Fig. 3 is a cross-sectional view of the main frame 25 taken along the line 3—3 of Fig. 1. In this figure there are shown by dotted lines certain parts of the traveling carriage.

Referring to the drawings, it will be noted that the mining machine comprises 30 two principal parts. One of these parts is the bed or main frame and is designated by 1. The other of the two principal parts is the movable cutter carrying frame which is designated by 2.

35 The main frame consists of two parallel connected parts 3—3, each comprising a single piece of structural rolled steel. I have shown in the drawings and I prefer to use channels, but it will be understood that 40 I-beams or any of the other suitable standard rolled shapes may be used. The webs of the channels are cut away at 4—4 for the sake of lightness. The forward end of the web of each channel is cut away, in a 45 similar manner, to a point near the center of the frame. The forward end of each channel, then, consists of two separated parts marked 5 and 6, respectively. Each 50 of the upper of these parts 5—5 is held in alinement with the main part of the frame and the entire smooth straight upper surfaces of the channels serve as tracks for the supporting rollers of the moving frame which will be more fully described herein- 55 after. I prefer to cut away the inner edge

of the upper flange of each of the channels. This makes the flange narrow and therefore gives greater clearance between the channels for the operating mechanism of the movable frame, and also gives a suitable bearing 60 surface for guides on the traveling frame. The lower part 6 of each channel is bent outward at 7 at an angle to the main part. This bending outward gives clearance space for the moving cutters and also provides 65 the frame with a wider base. I prefer to cut off the parts 6 at points behind the front of the machine. The forward ends of the parts 6 are united to the parts 5 by means of cast brackets 8 which are suitably 70 shaped to engage the two parts and are reinforced by ribs 9. At intervals along the bottoms of the channels are located cross connecting plates 10. At the forward end of the machine there is provided a connector 75 11 between the two frame parts 5—5. This connector 11 has a suitable slot adapted to engage with and guide the central bar 12 of the cutter frame. 13 and 14 are suitable jacks for securing the frame in place 80 when the machine is in operation.

The cutter frame and the actuating mechanism therefor which I prefer to use and which I have shown in the drawings is similar to that shown and described in my prior 85 Patent No. 684,356, granted October 8, 1901. The frame consists of the forward casting 15, the two side bars 17 and 18, and the central guiding bar 12. I prefer to form this central bar of a single rectangular forging. The three bars 12, 17 and 18 converge 90 toward the rear and are attached at their rear ends to the motor and gearing plate 19.

20 is a bearing depending from the plate 19. In this bearing is mounted the vertical 95 shaft 21 which carries a chain sprocket at its lower end. This sprocket engages with and actuates the chain 22 which is suitably supported and guided along the bars 17, 18 and the forward casting 15. The 100 shaft 21 is driven by means of the beveled gear wheels 23 and 24 from the shaft 25, which is, in turn, driven by means of the gears 26 and 27 from the motor 28. The plate 19 is supported on the main frame by 105 means of the four rollers 29—29.

30—30 are suitable depending lugs from the plate 19 which engage with the inner edges of the top of the main frame and prevent lateral movement. The lugs also have 110

outward extending projections adapted to engage the under side of the flanges and thus prevent any upward movement of the traveling frame.

5 31 is the feed shaft and carries at its ends pinions 32 which mesh with suitable racks 33 secured to the channels of the main frame just below the top flanges.

10 34 is a connecting shaft actuated from the shaft 25 by means of gearing 35. At its rear end it has a worm 36 adapted to engage with a suitable worm wheel 37 loose on the feed shaft.

15 38 is a connecting shaft similar to 34 but connected to the shaft 25 by means of a worm and wheel which rotate it in a direction opposite to that of the shaft 34 and at a slower speed.

20 39 is a worm similar to the worm 36 and likewise engages with a worm wheel loose on the feed shaft.

25 40 is a clutch attached to the feed shaft and which may be thrown in either direction by means of the lever 41 to engage with either of the two loose worm wheels.

30 In operation the machine, after having been properly located and secured, is driven by means of the motor 28. This motor, through the train of gearing before described, operates the chain with its attached cutters. The clutch 40 is thrown so that the feed shaft receives its power through the shaft 38 and the engagement of the rack wheels 32 with the racks 33 cause the whole 35 movable frame to travel bodily forward, the cutters being forced into the coal or other material which is being cut. The forward end of the frame is guided and supported by means of the bar 12 and the slotted cross bar 11. The rear end of the machine is supported by the rollers 29 which travel on the top of the channels 3. Lateral movement is prevented by means of the lugs 30. When it is desired to retract the movable 40 frame from the coal, the clutch 40 is thrown in the opposite direction and engagement is formed with the shaft 34 which rotates the feed shaft in the opposite direction and the cutter frame is drawn rapidly backward.

45 50 What I claim is:

1. In a mining machine, the combination of a movable cutter frame, and a stationary

frame comprising two rolled sections, each section being cut longitudinally throughout a part of its length, with the part on one side of said longitudinal cut bent outward at an angle to the main part, substantially as set forth. 55

2. In a mining machine, the combination of a movable cutter frame and a stationary 60 frame comprising two side sections of rolled metal, each section being split longitudinally throughout a part of its length, with one of the two adjacent parts thus formed bent at an angle to the other, substantially as set 65 forth.

3. In a mining machine, the combination of a movable frame, and a stationary frame comprising two rolled metal sections, each having a bottom flange, a top flange, and a 70 connecting web, the connecting web being cut away for a portion of its length, and the bottom flange adjacent said cut away portion being bent horizontally outward at an angle to the other parts of the section, 75 and brackets connecting the separated top and bottom flanges of each section, substantially as set forth.

4. In a mining machine, the combination of a movable cutter frame, and a stationary 80 frame comprising two rolled metal sections each having an upper flange, a lower flange, and a connecting web, the upper flange extending beyond the lower flange, a portion of the web being cut away between the two 85 flanges and a part of the lower flange being bent outward at an angle to the main part of the section, substantially as set forth.

5. In a mining machine, the combination of a movable cutter frame, and a stationary 90 frame comprising two rolled metal sections, each having an upper flange, a lower flange and a connecting web, a part of the web of each flange being cut away at one end to give clearance for the movable cutter frame, 95 and brackets connecting the two flanges of the sections at points adjacent the openings in the webs, substantially as set forth.

In testimony whereof I affix my signature, in presence of two witnesses.

HENRY B. DIERDORFF.
